J. A. B. SMITH

TYPEWRITING MACHINE

Original Filed July 25, 1919

10 Inventor:
Jesse A. Smith
by B. C. Flickney
Attorney.

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed July 25, 1919, Serial No. 313,142. Renewed May 13, 1921. Serial No. 469,378.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to the paper-carrying devices of typewriting machines, particularly Underwood and other round platen 10 front-strike machines.

One of the objects of the invention is to improve the means for typing entries upon 15 work-sheets, such as short bill-heads, that is to say, upon work-sheets receiving entries of say two or three lines, as for example a gas-light bill.

Heretofore, the use of typewriters for making out bills of this character has not been 20 found altogether satisfactory, because of the amount of handling of the bill which has been found necessary in introducing the same around the platen, then rolling it forward 25 and adjusting it to typing position, and providing for the making of the carbon copy, so that in practice the typing of a bill has not presented substantial advantages over the use of a pen.

30 In order to overcome these difficulties, I have contrived to introduce the bill into the machine and locate it at the typing position by a simplified operation, and in this way have made it feasible to type bills of this character much more rapidly than heretofore found practicable, so that the type-writer may successfully displace the pen in preparing these bills. I have also provided 35 simple means for producing carbon copies 40 of a succession of bills upon a single record-sheet.

In practicing the invention in its preferred form, the bill is not introduced at the back of the platen, as heretofore, but is inserted at the front thereof. The bill may be slipped down, bottom edge first, between the front of the platen and the usual platen-scales, or wing-scales which are arranged just in front thereof. A plate, tablet or 45 board is provided at the front of the platen for locating the bill. The fingers of the operator may press the bill back against this upstanding insertion or locating-plate, and

slide it along against a side gage, to bring the topmost blank line upon the bill to 55 proper typing position crosswise of the bill. The operator also slides the latter up against a gage provided at the top of the insertion or locating-plate. The bill may now be held by yielding clips. The bill is now ready, 60 because said gages are in such positions that the bill is in correct typing position, considered from top to bottom thereof. The side gage may be at the left-hand end of the insertion-plate or aligning plate, so that 65 the operator needs only to slip in the bill at the front, and then slide it along the plate as far as it will go to the left and upwardly to the top, and then operate the type-keys. In the Underwood typewriting machine, 70 there is usually a clear space between the front feed-rolls and the wing-scales, and the bottom edge of the bill may extend down into this space.

After the first line of the bill is written, 75 the typist may actuate a finger-piece which will mechanically move the insertion-plate bodily upward the distance of one predetermined line-space, thereby advancing the bill, and may then type the next line; and 80 this line-spacing or work-advancing operation may be performed still again if a third line is to be written upon the bill. Upon completing the typing of the bill, the insertion or bill-carrying plate may be restored to normal depressed position in readiness for receiving and advancing the next bill.

For making a carbon copy, a long record-sheet may be inserted around the platen and 90 behind the locating and advancing plate, and controlled in the usual manner by the feed-rolls thereon. As said sheet with its carbon is fed forwardly under the platen and up in front thereof, the operator, by 95 means of a finger-piece, may swing said locating-plate out of the way of the advancing record-sheet and its carbon, and said plate may be returned by a spring to normal position, just clearing the carbon and 100 record-sheet.

To enable this work-locating and advancing plate to be used for making entries at various heights upon the bills particularly to bring a certain line on a bill into register 105 with the printing line on the platen, or for

accommodating bills of different sizes, or for truing up the bill relatively to the printing line, the plate may be adjustably carried upon a support, and the line-spacing device for the plate may be effective on said support, thereby line-spacing the plate together with the work-sheet or bill upon it.

Other features and advantages will hereinafter appear.

10 In the accompanying drawings,

Figure 1 is a perspective view of part of an Underwood machine, showing my invention as applied thereto.

15 Figure 2 is a sectional side view of the same, showing a record-sheet being inserted.

Figure 3 is a view similar to Figure 2, but showing a bill in position and being typed.

Figure 4 is a fragmentary rear perspective view of the right-hand end of Figure 1.

20 Figure 5 is a view similar to Figure 3 but showing a bill being typed two lines lower down.

Figure 6 is a sectional detail showing a modification to effect line-spacing over a 25 greater distance.

Figure 7 is a spread perspective of some of the parts of Figure 4, viewed from the opposite side.

In making out bills upon the machine 30 shown, a record-sheet 10 together with its carbon sheet 11 is usually inserted first over the usual rear paper-table 12, and passed under the platen 13, between the platen and the front and rear feed-rolls 14 and 15. The 35 feed-rolls may be previously cast off, if desired, by depressing the usual casting-off handle 16. The record-sheet and its carbon, after passing the front feed-roll 14, pass beneath the usual paper-fingers 17, which 40 are resiliently mounted by the usual brackets 18 upon a rear cross-rod 19, and the sheets are guided upwardly by the deflecting plates 20. The feed-rolls 14 and 15 will advance the sheets when the platen is rotated 45 by the usual line-space handle 21 or the usual knob 22.

For writing the items upon a bill-head 23, it may be inserted from the front by inserting 50 its left-hand lower corner behind and below the top of the wing-scales 24, and be gaged against the side gage 25 at the left-hand end of an insertion-plate or tablet 26, and be at the same time slipped upwardly on the face of the plate 26, so that 55 its upper end catches under a spring clip 27, of which there is one at each end of the upper end of the plate 26. The bill-head is slipped up until its upper end strikes the top gage 28, which, in the illustrated embodiment of the invention, is 60 shown as in the form of a forwardly-projecting flange along the upper edge of the aligning plate 26. The clips 27 hold it in this position and it is then ready to be written upon if the insertion-plate 26 or front

paper-table has been properly positioned, for the gage 28 is to be so set that, if the insertion-plate is in its proper position, the top writing line upon the bill 23 is at the printing point. The insertion-plate 26 is 70 advantageously about the width of the bill-head 23, and its lower edge is formed as a toe 29 which rests almost upon the platen, but is clear of the platen, so that the record-sheet 10 and its carbon 11 slip easily under it.

Means are provided whereby the aligning plate 26 is movable by line-space stages or intervals to occupy a series or plurality of 80 different mechanically-determined line-space positions relatively to the printing line on the platen.

To write upon the second line of the bill-head 23, the insertion-plate 26 or gage-plate is adapted to be raised from its permanent 85 position the distance of one line-space, thus line-spacing the bill-head 23 which is carried along with it by the clips 27. To accomplish this line-spacing of the insertion-plate 26, there is provided a line-spacing 90 device including a finger-piece 30, herein shown as a knob, provided with a pointer in the form of a line 31^a, and which, when rotated, advances or line-spaces the insertion-plate 26, together with the sheet-holding 95 clips 27 and leading-edge gage 28 carried thereby. The connection for accomplishing this includes a rock arm 31, fast upon the shaft 32, upon which the knob 30 is fast. The rock arm 31 extends into a notch or opening 33 in a rear supporting plate or opening 34, which is fast to and supports the insertion-plate 26, being held thereto by a screw 35, threaded into an opening 36 and engaging the margins of a transverse slot 37 in the insertion-plate 26. This slot provides sufficient adjustment to enable a certain desired line on the bill 23 to be brought into register with the printing line 100 on the platen. In order to guide the insertion-plate 26 identically at both ends, there 105 is provided a second rock arm 38 on the opposite end of the rock shaft 32, and the plate 34 extends across beyond the second rock arm 38, both rock arms 31 and 38 engaging it. There are a screw 35 and corresponding slot 37 adjacent to each end of the supporting plate 34. The tablet or gage-plate 26 is mounted to occupy a single working position, but the screws 35 and slots 37 provide means for adjustment whereby it may be trued up at the printing line or adjusted to different heights to compensate for variations of the printing of the work-sheet or bill-head. The plate 34 and the insertion-plate 26 are adapted to be guided by screws 110 115 120 125 130 135 140 145 150 155 160 165 170 175 180 185 190 195 200 205 210 215 220 225 230 235 240 245 250 255 260 9810 9815

ed on a cross-rod 42 extending across the shift frame, there being a bracket 41 at each end of the supporting plate 34.

In order to mechanically determine the 5 line-space stages or intervals and to detain the insertion-plate 26 at any mechanically-determined line-space position to which it is set, there is provided a locating element in the form of a spring detent 43, fast upon 10 a connecting piece 44 of the bracket 41, and adapted to seat itself in any one of five notches 45, thus providing for one permanent position and four temporary positions of the table and gage 28. A bill-head to receive five line-spaces would have only 15 70 four spaces below the top printing line, and this much of a bill-head can easily be accommodated below the printing line in the ordinary Underwood typewriting machine, above the segment 62 and behind the wing-scales 24.

Variations may be resorted to within the scope of the invention, and portions of the improvements may be used without others. 20

Having thus described my invention, I 80 85 claim:

1. In a front-strike typewriting machine, the combination with a revoluble platen and an equipment of feed-rolls therefor adapted to hold a record-sheet thereon, of a line-spacing mechanism for the platen, a paper-table above and at the front of the platen, said paper-table wholly above the printing line and separated from the platen to permit the record-sheet to feed between said paper-table and the platen, a device for holding a work-sheet to said paper-table, and means to line-space the paper-table and the work-sheet held to it. 90

2. In a front-strike typewriting machine, the combination with a revoluble platen and front and rear feed-rolls therefor adapted to hold a record-sheet thereon, of a line-spacing mechanism for the platen, a paper-table above and at the front of the platen, a support normally holding the lower edge of said table adjacent the platen, said table mounted to be capable both of a tilting movement to enable the leading edge of the record-sheet to pass freely beneath it, and also of a line-spacing movement, a clip adapted to hold a work-sheet outside of the feed-rolls, and a finger-piece to move the paper-table by line-space intervals to effect line-spacing of the work-sheet clipped to it. 100

3. In a front-strike typewriting machine, the combination with a revoluble platen and an equipment of feed-rolls therefor adapted to hold a record-sheet thereon, of a line-spacing mechanism for the platen, a paper-table above and at the front of the platen, a device for holding a work-sheet upon the table, a mount for the table, means for adjusting the table upon the mount, and a finger-piece adapted to move the mount by line-space intervals to effect line-spacing of the work-sheet as it lies upon the table. 110

4. In a front-strike typewriting machine, the combination with a platen and a platen-frame having ends in which the platen is 120 125 130

To facilitate the passage of a record-sheet and its carbon beneath the insertion-plate 26, the plate is adapted to be swung far enough away from the platen to clear the record-sheet even though the sheet is so wide that it bellies out considerably between the fingers 17. To accomplish this, the bar 42 is shown as rotatably mounted in ears 52 of brackets 53, which are adapted to fit upon the cover-plates 54 of the ends of the shift frame, and to be held thereto by means of thumb-screws 55 adapted to be screwed into the usual threaded openings instead of the screws which usually hold the cover-plates in place. To permit the rod 42 to rock the plate 26, it is yieldingly held against turning by a key 56, which lies between the ears 52 of one or both of the brackets 53, and which is adapted to be pressed into the kerf 49 by a spring 57 of ordinary form. To enable the typist to easily rock the insertion-plate 26, the rod 42 is adapted to be turned by a finger-piece 58 held fast to its end by means of a screw 59. It will be observed that the plate or frame 34 forms an intermediate support or mount whereby the paper-table is carried upon rod 42, and that the latter also forms a main support whereby both table and frame 34 are carried upon the platen-frame.

As illustrated in Figures 1 to 4, inclusive, the billhead is adapted to be typed upon only three different line-spaces. The permanent position of the table 26 is when the detent and locator 43 is in the top notch 45. To enable the bill-head to be typed at a larger number of line-spaces, the rod or shaft 32, as shown in Figure 6, may be pro-

journaled, of an equipment of feed-rolls for the platen, brackets upon said ends, a main support between said brackets, a table upon said support, guides to enable the table to slide upon the main support, a clip for holding a work-sheet upon the table, means for line-spacing the table, and separate means for line-spacing the platen.

5. In a front-strike typewriting machine, 10 the combination with a platen and a platen-frame having ends in which the platen is journaled, of an equipment of feed-rolls for the platen, brackets upon said ends, a main support between said brackets, a table upon 15 said main support, guides upon the main support for the table, a finger-piece for moving the table at line-space intervals, a connection from the finger-piece to each end of the table to cause it to move parallel to 20 itself, and a device for holding a work-sheet to the table.

6. In a front-strike typewriting machine, 25 the combination with a platen and a platen-frame having ends in which the platen is journaled, of brackets upon said ends, a support between said brackets, a table upon 30 said support, said table mounted for line-space movement, means for holding a work-sheet upon the table to move therewith in line-feeding direction, and means for detaining the table in a succession of line-space positions.

7. In a front-strike typewriting machine, 35 the combination with a platen and a platen-frame having ends in which the platen is journaled, of brackets upon said ends, a support between said brackets, a table adjustable upon said support, to true the table relatively to the printing line, a device for 40 holding a work-sheet upon the table to move therewith in line-feeding direction, a finger-piece for moving said table by line-space intervals, and means for tilting the table to enable a work-sheet to pass beneath it.

45 8. In a front-strike typewriting machine, the combination with a platen and a platen-frame having ends, of brackets upon said ends, a table rising from the front of said platen, means supporting said table on said 50 brackets, the lower edge of said table being above the printing line, a rotatable shaft, arms fast to said shaft and engaging said table, a finger-piece for rotating said arms to slide the table line-space intervals upon the brackets, a detent for holding the table, and means upon the table whereby a sheet may be gaged and held by its leading edge.

60 9. In a front-strike typewriting machine, the combination with a platen, of a reciprocatable paper-table having a clip adapted to hold a work-sheet to the table, and means independent of the platen for bodily moving the table to line-space the work-sheet relatively to the printing line upon the platen, means being provided to predetermine the

extent of the advance and return movements of the table.

10. In a front-strike typewriting machine, 70 the combination with a platen, of a reciprocatable tablet erected at the front side of the platen and having at its top a leading-edge gage and means for detaining the sheet, said gage occupying a predetermined position relatively to the printing line, said tablet terminating at its lower end above the printing line, and means for moving said tablet and gage upwardly a predetermined extent to permit the typing of another line upon the sheet.

75 11. In a front-strike typewriting machine, 80 the combination with a platen, of a reciprocatable tablet erected at the front side of the platen and having at its top a leading-edge gage and means for detaining the sheet, said tablet terminating at its lower end 85 above the printing line, and means for moving said tablet upwardly step by step to permit the typing of a succession of additional lines upon the sheet.

90 12. In a front-strike typewriting machine, 90 the combination with a platen, of a reciprocatable tablet erected at the front side of the platen and having at its top a leading-edge gage and means for detaining the sheet, said tablet terminating at its lower end 95 above the printing line, said tablet and gage being movable from a predetermined position relatively to the printing line upwardly step by step to a succession of predetermined positions to permit the typing of a succession 100 of additional lines upon the sheet, and yielding means independent of the platen for detaining said tablet in any of such predetermined line-space positions.

105 13. The combination with a platen, of a reciprocatable sheet-positioning and carrying tablet extending therefrom, said tablet mounted both for movement away from the platen to facilitate the manipulation of a record-sheet upon the platen and passed under the tablet, and also for line-spacing movement, means for carrying a sheet with the tablet in line-spacing direction, and means for moving said tablet bodily upward 110 to effect line-spacing of the sheet carried thereon.

115 14. In a front-strike typewriting machine, 120 the combination with a platen, of a tablet wholly above the printing line at the front upper side of the platen and having at the top thereof a leading-edge gage and means for holding a work-sheet for typing upon the bottom margin thereof, a rock-shaft upon which said tablet is mounted for swinging away from the platen, said tablet being adjustable along said rock-shaft and also being mounted for up-and-down adjustment relatively to said rock-shaft, means for carrying a work-sheet with the tablet in 125 line-spacing direction, means for moving 130

said tablet bodily upward relatively to said rock-shaft to effect line-spacing of the sheet carried thereby, and means for independently line-feeding a record-sheet inserted 5 between said platen and said tablet.

15. In a front-strike typewriting machine, the combination with a platen, of a table wholly above the printing line at the front upper side of the platen and having at the 19 top thereof a leading-edge gage and means for holding a work-sheet for typing upon the bottom margin thereof, said table being mounted for adjustment both up and down and longitudinally of the platen, line-spacing 15 means for the platen for independently line-feeding a record-sheet inserted between said platen and said table, and entirely independent means for moving said table bodily upward to effect line-spacing of the sheet 20 held thereon.

16. In a front-strike typewriting machine, the combination with a platen, of a gage device having a normal position at the delivery side of the platen relatively to the 25 printing line to locate the leading edge of a work-sheet, sheet-holding means associated with said gage device, movable means upon which said gage device is mounted and guided to have a temporary shifting movement to a predetermined extent relatively to the printing line on the platen for affording a re-positioning of the same work-sheet to permit the writing of a succeeding line thereon, and co-operative locating devices to 35 locate said gage device mechanically in its normal and temporary positions.

17. In a front-strike typewriting machine, the combination with a revolvable platen, of a table erected at the front side of the platen 40 and having at its top a fixed leading-edge gage and also having means for detaining a sheet, said table terminating at its lower end above the printing line, so that the lower margin of the sheet may project below the 45 table, to be typed upon, said table and gage being adjustable from a predetermined normal position to a temporary predetermined line-space position to permit typing of an additional line upon the sheet, and line-spacing 50 mechanism comprising relatively yielding co-operative devices for locating and detaining said table and gage in either normal or temporary position, while permitting the table and gage to be pressed from one 55 position to the other.

18. In a typewriting machine, the combination with a revolvable platen, of a gage at the delivery side of the platen for the leading edge of a work-sheet, said gage being mounted above the printing line, to position 60 a work-sheet relatively to the printing line, manually-controlled means to advance said gage by a predetermined line-space interval and there to detain it, preparatory to 65 typing another line upon the work-sheet,

and means to detain a work-sheet in position during the typing operation with its leading edge against said gage at either adjustment of the latter.

19. In a front-strike typewriting machine, the combination with a revolvable platen, of a leading-edge gage having a normal position at the delivery side of the platen above the printing line and provided with means for adjustment whereby it may be trued up at the printing line or adjusted to compensate for variations of the printing of a work-sheet, manually-operable means for affording an adjustment of said gage bodily upward from normal position 70 to a temporary predetermined position to permit a second line to be typed upon a work-sheet held against said gage, co-operative means being provided to locate the gage mechanically in its normal and temporary 75 positions, and means to hold the work-sheet in position with its leading edge against said gage during such adjustment.

20. In a typewriting machine, the combination with a revolvable platen, of a leading-edge gage having a normal position at the delivery side of the platen, means whereby said gage is adjustable to a temporary position to permit an additional line to be typed upon a work-sheet gaged thereby, co-operative locating devices being provided to locate the gage mechanically in its normal and temporary positions, and means to maintain the sheet in position with its leading edge against said gage during such adjustment. 95

21. In a front-strike typewriting machine, the combination with a platen and a platen-frame, of an aligning table at the delivery side of the platen and having a leading-edge gage, said aligning table and leading-edge gage mounted for reciprocating movements between normal and temporary line-space positions, and means, including automatically co-operative locating 105 devices associated with said aligning table and said platen-frame, for mechanically locating and detaining said table and gage in said normal and temporary positions. 110

22. In a front-strike typewriting machine, the combination with a platen, of an aligning table at the front of the platen above the printing line, a mount upon which said aligning table is carried, said table being adjustable relatively to said mount, 115 to true the table relatively to the printing line, said mount being adjustable to different mechanically-located line-space positions relatively to the printing line for correspondingly repositioning said aligning table, and means for holding a work-sheet 120 on said table during the adjustment of said mount. 125

23. In a front-strike typewriting machine, the combination with a platen, of an 130

- aligning plate erected at the front of the platen above the printing line and provided with a leading-edge gage, a mount upon which said aligning plate is adjustable relatively to the printing line, and a support upon which said mount is settable by mechanically-determined line-space stages or intervals to occupy a series of different line-space positions relatively to the printing line for correspondingly repositioning said plate and leading-edge gage, and means for holding a work-sheet on said plate and against said gage in any of the positions of the latter.
- 15 24. In a front-strike typewriting machine, the combination with a platen, of a leading-edge gage at the delivery side of the platen above the printing line, said gage being adjustable step by step to a series of spaced positions relatively to the printing line, and means for mechanically locating said gage in any of said positions, said gage being also adjustable independently of said locating means and relatively to the printing line to positions intermediate to said mechanically-located positions.
- 20 25. In a front-strike typewriting machine, the combination with a platen, of a gage-carrying mount adjustable relatively to the printing line, means being provided for mechanically locating said mount at different line-space positions, and a leading-edge gage upon said mount and adjustable relatively thereto.
- 25 26. In a front-strike typewriting machine, the combination with a platen, of a plate-carrying mount settable to occupy a series of mechanically-determined spaced positions relatively to the printing line, and an aligning plate provided with a leading-edge gage and adjustable upon said mount to positions intermediate to said mechanically-determined positions.
- 30 27. In a front-strike typewriting machine, the combination with a platen, of a collating table at the front of the platen above the printing line, means carried by the table for holding a work-sheet on the table, a leading-edge gage for the work-sheet carried by the table, supporting means for the table on which the table is mounted for adjustment whereby the table and the sheet-holding means and the leading-edge gage may all be trued up relatively to the printing line or adjusted to compensate for variations of the printing of the work-sheet, and a support upon which said supporting means may be adjusted to occupy a series of mechanically-determined spaced position at different heights relatively to the printing line.
- 35 28. In a front-strike typewriting machine, the combination with a platen, of a table at the delivery side of the platen, a support for said table, said table being provided with a leading-edge gage and a side gage, and line-spacing means, including a locating element connected with said gage and a co-operative locating element mounted on said support, for mechanically locating and detaining said table on said support at different line-space positions.
- 40 29. In a typewriting machine, a platen, a table above the platen having means to hold a work-sheet in position for printing against the platen, a plate for supporting the table and a support for the supporting plate permitting adjustments of both the table and the plate and also the work-sheet in the plane of the table for line-spacing the work-sheet.
- 45 30. In a typewriting machine, a platen, a table above the platen with gages thereon to hold a work-sheet in proper position for printing against the platen, a supporting plate for supporting both ends of the table, and a support for the supporting plate permitting adjustments of both the plate and the table for line-spacing the work-sheet.
- 50 31. In a typewriting machine, a platen, a table above the platen, a supporting plate for the table, and a support for the supporting plate permitting adjustments of both the table and the plate and also the work-sheet both vertically and longitudinally of the platen as described.
- 55 32. In a typewriting machine, a platen, a table above the platen having means to hold a work-sheet for printing against the platen, a supporting plate for supporting the table, and a support for the supporting plate, fixedly maintained in its position relative to the platen, said support having means to adjust both itself and the table relatively to the platen to provide for line-spacing.
